INVENTOR

UNITED STATES PATENT OFFICE.

HARRY JAMES, OF DENVER, COLORADO.

POLE-ANCHORING BASE.

1,290,563.

Application filed March 26, 1917. Serial No. 157,826.

Patented Jan. 7, 1919.

To all whom it may concern:

Be it known that I, HARRY JAMES, a citizen of the United States, residing in the city and county of Denver and State of Colorado, have invented a new and useful Improvement in Pole-Anchoring Bases, of which the following is a full and complete description and specification, reference being had to the accompanying drawing, which 10 is hereby made a part thereof.

This invention relates to that class of device wherein a pole or post is raised upon, and firmly, though detachably, fastened to an anchoring base.

15 The objects and purposes of this invention are:—to provide a stable anchoring base for poles and posts; to provide a means whereby the life and service of poles and posts may be greatly extended; to facilitate 20 and cheapen the making of repairs where poles or posts have become broken off or rotted off at or near the ground, or of making replacements where poles or posts have been in any manner destroyed; and generally, to improve the workability and effectiveness of this class of device.

25 The invention consists in certain novel features of construction of the several parts, and particularly in their combination, as 30 hereinafter shown and described, and set forth in the accompanying claim.

In the drawing illustrating the invention, Figure 1 shows, in elevation, the device in operation in attachment with a pole or post.

35 Fig. 2 represents the top view of cap B., detached from the remainder of base A., and from the other elements of the device.

Fig. 3 represents the bottom view of cap B., detached as before.

40 Fig. 4 represents a sectional view of cap B., in elevation, along line *xy* in Fig. 2.

Fig. 5 represents a part of the means of attachment between cap B., when in place upon the remainder of base A., and a pole 45 or post F. raised thereon.

Figs. 6, 7 and 8 represent various views of another element in the said means of attachment between the base and a pole or post. In Fig. 6 the element or part is shown 50 ready for use in the device. In Fig. 7 the general plan of its construction is indicated, wherein a flat piece of metal, cut in the form shown, is designed to be bent along the various dotted lines into the form dis-

closed in Fig. 6. Fig. 8 is an edgewise view 55 of the part shown in Fig. 7, looking from either the right or left side.

Fig. 9 represents another element in the said attaching means.

In the various views shown, the same letters refer to the same parts throughout. Where there are several similar parts, they are indicated by the same letter, prime, second or third, as the case may be.

A. represents a concrete base, molded in 60 the general form indicated in Fig. 1, and provided interiorly, in the direction of its length, with four reinforcing rods *a*, *a'*, etc., which also serve as a part of the means of attachment between base A. and cap B., 70 inasmuch as the upper ends of these rods are adapted to pass through and hook upon appropriate webs, *e*, *e'*, etc., constructed in cap B.

B. represents a metal cap upon the top 75 of base A., placed in proper position at the time the latter is molded. This cap is specially constructed in such manner as to insure fixed and rigid attachment to the remainder of base A. This is brought about 80 by so constructing the cap that viewed from below, as in Fig. 3, it is provided with alternate solid and hollow parts, into which latter the concrete enters at the time of molding, and becomes solidified therein. 85 This attachment between base A. and cap B. is further strengthened and reinforced by the rods *a*, *a'*, etc., above mentioned. The arrangement of these solid and hollow parts of cap B. are best indicated in Fig. 3, and 90 will be more fully described hereinafter.

C., *C'*, etc., represent four similar rods designed to be disposed at equal intervals about the circumference of pole or post F., and so constructed in respect to one end 95 thereof, *f*, *f'*, etc., as to fit into appropriate parts, *c*, *c'*, etc., in cap B.

D., *D'*, etc., are four similar parts designed to be fixed in the pole or post F. at 100 equal intervals about its circumference, some distance above its base, and each designed to receive respectively the upper end of one of the rods C., *C'*, before mentioned, which upper ends are provided with means, *o*, *o'*, etc., to tighten and fasten the engagement effected, through rods C., *C'*, etc., between attachments D., *D'*, etc., and cap B.

E. represents a means of fastening and

- supporting the parts D., D', etc., E'. represents a similar means of holding and fastening the rods C., C', etc., in proper position and engagement with the other elements of the device, when fully assembled. Both E. and E' are shown to be adjustable to different sizes of poles or posts through the operation of designated means of tightening and fastening, respectively p. and p'.
 10 The construction of cap B. is as follows. The top is solid, except for four slots c., c', etc., disposed along two diameters of the top which are at right angles with each other. These slots extend inward in the cap about half its diameter and downward for about half its depth. They are so constructed as to receive and fit the ends f., f', etc., of the rods C., C', etc. These ends of these rods are constructed as indicated, in the form of a ball larger in diameter than the remainder of the rod. The position of the rods is adjustable throughout the length of the slots, thereby rendering the same device usable with poles or posts of differing diameters.
 15 The top of the cap B. is provided on its upper surface with two transverse wedge-shaped ridges d., d', disposed at right angles to each other, and passing between the slots c., c', etc., above mentioned. These ridges serve to strengthen the top of the cap B., and also to engage the butt end of the pole or post and obviate its movement about on the cap when erected thereon. The cap B., below the top mentioned, consists of
 20 two concentric rings, the interior one being about half the diameter of the exterior. Between these two rings are disposed at regular intervals certain solid portions. Between these, and also within the interior ring, are the hollow parts mentioned earlier in this description. These solid portions are of two sorts: e. e', etc., the webs above referred to, which are the full depth of the cap, and are provided with holes g., g', etc.,
 25 to receive the reinforcing rods a., a', etc., as hereinbefore described; and i., i', etc., which are only about half the depth of the cap B. and are designed to contain the slots c., c', etc. The hollow parts or spaces within the cap B. are designated, respectively, h., the space within the interior ring, and b., b', etc., the spaces between the webs e., e', etc. It will be observed that these latter spaces contain the parts i., i', etc., disposed
 30 for the accommodation of the slots c., c', etc., as before described, and depending into the said spaces at their meridian points for about half their depth.
 The parts D., D', etc., are each constructed by disposing the parts j., j', k., k', l., and m., shown in Fig. 7, into the form disclosed in Fig. 6, by bending along the dotted lines indicated in Fig. 7. j., j', Fig. 6, are designed to be driven into the body of the pole
 35 of post F. so that l. rests against the pole or post and m. stands out at right angles thereto, and is supported in that position by k., k', which serve as brackets or braces, and are designed to fit snugly against band E., which in turn is placed and fastened around the pole or post and over l., as indicated. The tightening and fastening means of this band E. are indicated by p. The four similar parts, D., D', etc., constructed and attached as above, are so disposed at equal intervals about the circumference of the pole or post that, when the latter is raised upon the cap B. of base A., the hole n. in each of the parts m. in the said parts, D., D', etc., will be directly over a corresponding slot c., c', etc., in cap B., previously described.
 40 To complete the entire attachment of the device, the ends f., f', etc., of rods C., C', etc., are then passed from the outer edge of cap B. into the slots c., c', etc., and brought into close engagement with the circumference of the pole or post, the upper ends of each of said rods having been passed through the corresponding hole n. disposed in each of the parts D., D', etc., as previously described. These rods are then tightened and fastened in place by appropriate means, indicated by o., o', etc. Band E' is then adjusted in position, encircling the rods as indicated, and tightened and fastened by means p'.
 While I have shown and described particular and specific forms of construction in certain of the parts and elements herein, I do not intend in any wise to limit myself to them solely, and I hereby expressly reserve the right to make any changes within the scope of the invention disclosed.
 45 My claim is:—
 In pole anchoring-base devices, a cementitious base, provided with a metal cap, which is permanently fixed and incorporated as the top thereof, and which is provided upon its upper surface with appropriate means to prevent the butt of the pole or post placed upon it from slipping or twisting about, and which is likewise provided in its upper portion with a series of appropriate radial slots, so constructed that the lower portion of these slots, in the body of the cap, is cylindrical in form and of greater diameter than the upper portion which is open through the upper surface of the cap; a series of appropriate members designed to engage adjustably in these slots and to rise upward from the cap about the circumference of the pole or post raised thereon, such members being constructed to consist of a bar or rod provided with a globular part at one end of greater diameter than the rod, which globular part is designed to enter into, and fit adjustably in,

the cylindrical portion of the slot described, while the adjacent portion of the rod itself passes, adjustably, into the upper part of the slot described; together with appropriate means of adjustably attaching such members to such pole or post, substantially as described.

In witness whereof, I have hereunto attached my signature in the presence of two witnesses.

HARRY JAMES.
